US00D937866S

(12) **United States Design Patent** (10) **Patent No.:** **US D937,866 S**
Ueda (45) **Date of Patent:** **** Dec. 7, 2021**

(54) **DISPLAY SCREEN OR PORTION THEREOF
WITH GRAPHICAL USER INTERFACE**

(71) Applicant: **Nissan Motor Co., Ltd.**, Kanagawa (JP)

(72) Inventor: **Jun Ueda**, Kanagawa (JP)

(73) Assignee: **Nissan Motor Co., Ltd.**, Yokohama (JP)

(**) Term: **15 Years**

(21) Appl. No.: **29/728,879**

(22) Filed: **Mar. 23, 2020**

(30) **Foreign Application Priority Data**

Sep. 24, 2019 (JP) 2019-021262
(51) **LOC (13) Cl.** **14-04**
(52) **U.S. Cl.**
USPC **D14/486**

(57) **CLAIM**

The ornamental design for a display screen or portion thereof with graphical user interface, as shown and described.

DESCRIPTION

The single FIGURE is a front view of a display screen or portion thereof with graphical user interface showing our new design.

The broken line showing of a display screen or portion thereof is for for illustrative purposes only and forms no part of the claimed design. The dot-dash lines shown in the FIGURE are only to indicate a boundary between a claimed design and non-claimed portions, and form no part of the claimed design.

1 Claim, 1 Drawing Sheet
